UNITED STATES PATENT OFFICE.

ROBERT HUTSEL, OF KINGSTON-UPON-HULL, ENGLAND, ASSIGNOR TO AMERICAN RADIATOR COMPANY, OF CHICAGO, ILLINOIS, A CORPORATION OF NEW JERSEY.

CASING OR JACKET FOR BOILERS.

1,239,106.

Specification of Letters Patent.

Patented Sept. 4, 1917.

Application filed May 3, 1916. Serial No. 95,076.

To all whom it may concern:

Be it known that I, ROBERT HUTSEL, a citizen of the United States, but at present residing at Kingston-upon-Hull, in the 5 county of York, England, have invented certain new and useful Improvements in Casings or Jackets for Boilers; and I do hereby declare the following to be a full, clear, and exact description of the invention, 10 such as will enable others skilled in the art to which it appertains to make and use the same.

This invention has reference to improvements in casings or jackets for boilers of 15 that type which are designed more especially for heating water or generating steam to be passed through pipes, radiators and the like for heating houses, institutions and buildings generally by hot water or steam 20 heat, or for supplying hot water for domestic purposes, or for both of these purposes.

My invention consists of an arrangement of metal sheets, preferably sheet iron, provided with hook-like edges connected by 25 means of slides or keys also having hook-like edges, the hook-like edges of the slides or keys engaging the hook-like edges of adjoining metal sheets, those vertical slides or keys which engage and connect the meeting edges of two metal sheets at what would 30 form a corner of the casing or jacket being provided with a cap-like top.

In the accompanying drawings which illustrate my invention, Figure 1 represents 35 a plan view of one corner of a square or similarly shaped boiler casing or jacket in accordance with my invention, part of the cap on the top of the corner slide or key being broken away to allow of such corner 40 slide or key and the hook-like edges of the metal sheets of the casing or jacket which it engages, being seen, the top of the casing or jacket being omitted, Fig. 2 is a perspective view of one corner of the casing or 45 jacket showing the corner slide or key with its cap and the slides or keys which connect the top to the sides or to one side and one end member of the casing or jacket, in position, Fig. 3 is a plan view of a portion of 50 each of two metal sheets in the same plane to form say one side of the casing or jacket when more than one sheet is employed in the formation of a side, and the slide or key for connecting the same. Fig. 4 represents 55 a side view of a portion of one of the cor-

ner slides or keys and its cap-like top, Fig. 5 is a plan view, Fig. 6 a view on the line 1—2 of Fig. 5, and Fig. 7 a front view of same.

Similar reference characters refer to similar parts throughout the several views.

Referring to the drawings, A and B indicate a portion of each of two of the metal sheets which constitute two side members, or one side member and one end member 60 of the casing or jacket, a and b the vertical hook-like edges on the inner ends and a¹, b¹ the longitudinal hook-like edges on the top of such sheets. C (Fig. 1) indicates hair-felt, asbestos board or like non-conducting 65 material secured to the inner face of the metal sheets, and B indicates a portion of the metal sheet which forms, or of one of the metal sheets which form the top of the casing or jacket, d, d¹ being the hook-like 70 edges of such sheet.

E and F indicate two angle-shaped metal slides or keys for connecting the top sheet or sheets D to the side sheets A and B, e indicating the hook-like edges of the slide 80 or key E which engage the hook-like edge d of the top sheet D and the hook-like edge a¹ of the side sheet A, f indicating the hook-like edges of the slide or key F which engage the hook-like edge d¹ of the said 85 top sheet D and the hook-like edge b¹ of the side sheet B.

G indicates a portion of one of the vertical slides or keys which secures two metal side sheets of the casing or jacket together where 90 they meet to form a corner, and g, g are the hook-like edges of such slide or key which engage the hook-like edges a and b on adjoining ends of the side sheets A and B respectively.

H indicates a metal cap, preferably of cast iron with which the slide or key G is provided, the said cap being secured to the top of the slide or key, the means by which it is secured thereto being shown in the drawings as rivets h, h, but it may be secured thereto by brazing, welding or any other suitable means. The cap H is of angular shape and is secured to the outside of the slide or key, the angular portion or ridge of the slide or key fitting in one of the angles of the cap. The top of the cap projects over the top of the slide or key and also to a certain extent over the top of the corner of the casing or jacket, and the two side por- 110

tions of the cap project to a certain extent over the sides of the two adjoining portions of the casing or jacket, as shown at Figs. 1 and 2 of the drawings, such cap not only 5
5 imparting a neat appearance to the top corner of the casing or jacket but provides a means for enabling the slide or key to be pushed into engagement and withdrawn from engagement with the hook-like edges 10
10 of the metal sheets it is designed to secure, and also for covering the sharp edges of the top of the slide or key and those ends of the longitudinal slides or keys which connect the top of the casing or jacket with the 15
15 sides or the sides and ends of the casing or jacket, which terminate at the corners.

In cases where the top and the sides or the sides and ends of the casing or jacket are each built up of a plurality of metal 20
20 sheets, the adjoining edges of adjoining sheets which form the top or the particular side or end are of hook-like formation and are connected by means of flat slides or keys J having hook-like edges j, j which engage 25
25 the adjoining hook-like edges k, k of the sheets, as shown at Fig. 3.

I claim:—

1. A boiler jacket comprising a plurality of sections having vertical and horizontal 30
30 edges, and locking members engaging said edges to maintain said sections in their assembled positions, certain of said locking members being provided with end portions inclosing the corners of the sections which 35
35 form the corners of the jacket, substantially as specified.

2. A boiler jacket comprising a plurality of sections having vertical and horizontal edges, and locking members engaging said 40
40 edges to maintain said sections in their assembled positions, certain of said locking members being provided with end portions inclosing the meeting edges of the corners of the sections which form the corners of 45
45 the jacket, substantially as specified.

3. A boiler jacket comprising a plurality of vertical and horizontal sections, a lock-

ing member slidably engaging the adjacent edges of certain of said sections and having a permanently formed end portion engaging certain other of said sections to limit the sliding movement of said locking member, substantially as specified. 50

4. A boiler jacket comprising a plurality of vertical and horizontal sections forming 55
55 the sides, ends, and top of the jacket, and locking members slidably engaging the edges of adjacent vertical sections and having permanently formed end portions engaging the top of the jacket to limit the 60
60 sliding movement of said locking members and to hold them in position, substantially as specified.

5. A locking member for boiler jacket sections comprising a longitudinally extending 65
65 body portion provided with locking means, and a permanently formed end portion extending transversely with respect to said body portion, substantially as specified.

6. A locking member for boiler jacket sections comprising a longitudinally extending 70
70 body portion consisting of angularly disposed side members provided with locking means, and a permanently formed end portion 75
75 extending transversely with respect to said side members and registering with the angle formed thereby, substantially as specified.

7. A locking member for boiler jacket sections comprising a longitudinally extending 80
80 body portion consisting of angularly disposed side members provided with locking means, and a cap shaped member secured to one of the ends of said side members and having a portion extending transversely with respect to said side members and registering with the angle formed thereby, substantially 85
85 as described.

In testimony whereof I affix my signature in the presence of two witnesses.

ROBERT HUTSEL.

Witnesses:

HOGGIT COLBECK,
LOUIS EDGAR KIPPAC.
